UNITED STATES PATENT OFFICE.

HARRY SEBELL, OF BOSTON, MASSACHUSETTS.

CONTAINER.

Application filed December 18, 1923. Serial No. 681,340.

To all whom it may concern:

Be it known that I, HARRY SEBELL, a citizen of the State of Russia, and resident of Boston, county of Suffolk, State of Massachusetts, have invented an Improvement in Containers, of which the following description, in connection with the accompanying drawing, is a specification, like characters on the drawing representing like parts.

10 This invention relates to a container and the general object thereof is to provide a container which is very strong at its rim.

Another object of the invention is to provide a container which may easily and securely be sealed.

20 A further object of the invention is to provide a container which may easily be opened by the consumer and which may easily, quickly and securely be closed by the consumer after a part of the contents has been used.

Other objects and features of the invention will more fully appear from the following description and accompanying drawings and will be particularly pointed out in the claims.

The drawings illustrate in section, detail and elevation a preferred form of construction adapted for use in a container and embodiment the broad principles of the invention.

In the drawings:

Fig. 1 is a partial section longitudinally through the container;

Fig. 2 is a detail of the rim of the container showing the method of opening and one form of sealing strip;

Fig. 3 is a detail of the rim of the container showing another form of sealing strip;

40 Fig. 4 is a partial elevation of the container showing one type of end for the sealing strip;

Fig. 5 is a partial elevation of the container showing another type of end for the sealing strip.

Only such parts of the container as are necessary to illustrate the invention have been shown. As illustrated herein the container comprises a body 1 and a top for closing the container designated generally at 2. The end of the body of the container is bent at 3 to present a peripheral flange 4 lying on the exterior of the container and substantially parallel with the body. The top of the container is bent at 5 to present a peripheral flange 6 which fits closely against and over-

lies the body flange as illustrated in the drawings.

In order to securely seal the container a U-shaped sealing strip 7 is provided having 60 parallel wings 8 and 9 for embracing the flanges 4 and 6. The sealing strip is of such a length that it extends entirely around the container and overlaps at 10. The wing 9, as illustrated, fits up in between the body 65 flange 4 and the body 1 of the container and the other wing 8 of the sealing strip surrounds the flange 6 of the top. The sealing strip, while U-shaped in cross section, may have various forms two of which have been 70 illustrated. The sealing strip shown in Figs. 1 and 2 has wings which are of equal length and parallel with one another throughout while the sealing strip shown in Fig. 3 has the wing 8 extended at 11 partially to overlie the bend 5 of the closure flange thus providing a rim which is exceptionally strong and on which the sealing strip is held very securely, but from which the strip may be readily removed. Both forms of the sealing 75 strip, however, are U-shaped in cross section.

When the sealing strip is in position and the container is closed at the factory the flanges and locking strip are firmly pressed against the body of the container with all 80 the layers of the metal parallel thus providing a very strong rim for the container but also one which takes very little space since there is no wide flange projecting from the wall of the container. In order to provide 85 a more rigid rim the top is made with a depressed central portion 12 and a wall 13 which fits closely against the inner face 14 of the body of the container. Thus when the container is sealed at the factory and 90 the rim is crimped, there are six thicknesses of metal at the rim of the container, namely, the flanges 4 and 6, the wings 8 and 9 of the sealing strip, the body 1 of the container and the wall 13.

A container having the bends 3 and 5 in the body and top thereof respectively and having a U-shaped sealing strip is very easy to seal. When the body and top of the container are stamped out the bends 3 and 105 5 provide grooves 15 and 16 and another groove 17 is provided within the U-shaped sealing strip. During the process of making the container these grooves 15, 16 and 110 17 are filled with a cement or sealing compound before the top or the sealing strip are put in place. The sealing compound is

a liquid when it is put in the grooves but hardens as it dries and by so positioning the parts of the container and sealing strip, while the parts are separate and prior to assembling the container, that the flanges and wings point upwardly, the sealing compound is retained within the grooves and prevented from running out until it dries. When the container is assembled the top is forced into position over the body and the sealing strip is put in position embracing the flanges 4 and 6. The sealing compound in the grooves makes an absolutely air tight joint at the rim of the container.

15 An important feature of the invention is the means by which the container may easily be opened by the person who uses the contents thereof. In opening the container it is first necessary to remove the sealing strip.

20 In order to accomplish this easily without the use of a can opener or other special tool, means are provided to enable the overlapping end of the strip easily to be withdrawn from around the flanges to start the removal of the strip. For this purpose a slot 18 may be cut in the overlapping end of the strip so that a sharp pointed instrument such as the prong of a fork or the point of a knife can be wedged under the strip to start its removal. If desired the wings of the strip may be spread and the slot enlarged to provide a finger hold 19 which is then twisted to lie next to the body of the container directly under the sealing strip so as to take up no more space than does the rim.

In opening the container after the sealing strip has been removed it is necessary to remove the top and in order to enable this to be easily accomplished the peripheral flange 6 normally projects at 20 beyond the edge of the flange 4. Thus when opening the container after the sealing strip has been removed all that is necessary is to press the edge 20 of the flange 6 against the edge of a table 21 which will break the sealing compound in the groove 16 and start the removal of the top. After the sealing compound has been broken and the removal started it is a simple matter to lift the top entirely from the container. If it is desired to close the container again after a portion of the contents has been removed the top is placed on the container and then may easily be driven down into position by a blow of the hand and when it is desired to remove the top a second time it is merely necessary to press the edge 20 of the flange 6 against the table 21 again to start the removal of the top.

The body of the container may be and preferably is slightly raised at 22 to provide a projection which bears against the bend of the sealing strip to serve as an additional means for holding the sealing strip

in place with the wings embracing the flanges.

A container having the construction above described is extremely well sealed not only because of the number of grooves in which the sealing compound may be placed but also because of the number of firmly contacting surfaces between which the contents of the container would have to pass before it could escape. When the top and body of the container are stamped out the bend 5 and the bend 3 are made of such a radius that when the parts are in position as shown in Fig. 1, all of the adjacent surfaces are in firm contact with one another and press the sealing compound between them. When the container is assembled the top is pressed on the body with great force so that the convex surfaces of the bend 3 tightly fits within and bears against the concave surface of the bend 5. Thus when the container is completely assembled the contents in escaping would have to pass between the body 1 and the wall 13, then through the sealing compound in the groove 16, then between the flanges 4 and 6, then through the sealing compound in the groove 17, then either between the flange 6 and the wing 8 or between the flange 4 and the wing 9, through the sealing compound in the groove 15 and between the wall 1 and the wing 9. When the container has been once opened and then closed the contents must pass between the body 1 and wall 13, and then between the bends 3 and 5, and then between the flanges 4 and 6 in order to escape. The top is firmly held in position on the container after it has been once removed and then replaced by the frictional engagement of the wall 13 with the body of the container and by the frictional engagement of the flanges 4 and 6. In order to more firmly hold the top in position the flanges 4 and 6 and other parts of the rim of the container may be made of metal having some spring to it so that the flanges 4 and 6 and the parts 1 and 13 press against one another due to the resilience of the metal.

Although a particular form of the invention has been described it is to be taken as illustrative only as many changes in the construction of the container, such as the lengthening or shortening of the edge 20 of the flange of the top or the edge 11 of the wing 8, may be made without departing from the spirit of the invention. It is, therefore, desired that the invention be construed as broadly as the limitations in the claims, taken in conjunction with the prior art, may allow.

Having thus described the invention what is claimed as new and desired to be secured by Letters Patent is:

1. A container having an open top and a peripheral flange on its exterior at the top

- which is parallel to the walls of the container but spaced therefrom, a top for closing the container, said top having a depressed central portion and an upstanding wall 5 which fits within the opening of the container, said top having a depending flange extending from said upstanding wall and fitting closely against the peripheral flange, and a removable sealing strip U-shaped in 10 cross section extending around the container with one wing thereof between the peripheral flange and the body of the container and the other wing surrounding the flange of the top, the flanges and sealing strip being firmly 15 pressed against the exterior wall of the container and the upstanding wall of the top being firmly pressed against the interior face of said container.
2. A container comprising a body having an interior face and an exterior face and presenting a peripheral flange on the exterior of the container parallel with the body, a top for closing the container having a depressed central portion and a wall joining the central portion and fitting closely 25 against the interior face of the body, a flange extending from said wall of the top fitting closely against the body flange and projecting beyond the edge thereof, and a removable sealing strip U-shaped in cross section 30 extending around the container with one wing between the body flange and the body of the container and the other wing surrounding the flange of the top, the flanges and sealing strip being firmly pressed 35 against the exterior face of the body of the container and the wall being firmly pressed against the interior face of said body.

In testimony whereof, I have signed my name to this specification.

HARRY SEBELL.
